RACK

William J. Fishel, Winston-Salem, N. C.

Application April 26, 1943, Serial No. 484,623

4 Claims. (Cl. 211—60)

This invention relates to a rack designed primarily for holding heavy, slender articles on end, such as pipes, axles, rods, etc.

An object of the invention is to provide a rack which will tightly grip the inserted articles and support them in upstanding positions.

Another object is to provide a rack which is simple and compact in construction and will not readily get out of order, it being possible to use the rack for holding long, slender articles of different diameters or thicknesses.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawing the preferred form of the invention has been shown.

In said drawing:

Figure 1 is a front elevation of a portion of a rack embodying the present improvements, one of the gripping elements being shown in engagement with a supported article.

Figure 2 is an enlarged vertical section illustrating one of the units of the rack, the same being shown by full lines in normal position and by dotted lines in loaded or gripping position.

Figure 3 is a section through a portion of one of the units.

Figure 4 is a bottom plan view of said unit.

Referring to the figures by characters of reference, 1 designates the body portion of the rack which can be in the form of a box of sheet metal or other material of any proportions desired. This body or casing is provided with a horizontal partition 2 spaced from and parallel with the top of the body and having spaced openings 3 which are coaxial with other openings 4 formed in the top of the body. The openings 3 are of less diameter than the openings 4 and each pair of openings comprising a top opening 4 and a lower opening 3 is adapted to receive one of the holding units of the rack.

As shown particularly in Fig. 2 the holding unit includes a funnel-like base 5 the small lower end of which opens into a tubular stem 6 which is slidable within the opening 3 and is limited in its upward movement by a transverse pin 7 extended through the stem and under the partition 2. A coiled spring 8 is mounted on the stem and is interposed between the funnel 5 and the

partition 2 so as to constitute a yielding support for the unit.

Extended upwardly from the wall of the unit are elongated, resilient arms 9 which extend through the opening 4 and are provided, at their upper ends, with radially extended wedges 10 formed with or secured to the outer sides of the arms. When the unit is in its raised or normal position where it is supported by spring 8, the lower ends of the wedges are within the opening 4 and the arms 9 are substantially parallel.

When it is desired to support an elongated article such as a pipe, rod, axle or the like, in this rack, the same is placed in an upright position above the opening into which it is to be inserted. It is then lowered between the arms located in said opening until the bottom end of the inserted object comes into contact with the funnel 5. The funnel is then thrust downwardly under the weight of the inserted article and against the action of the spring 8 and this will cause the wedges 10 to ride downwardly within the opening 4 and to be deflected toward each other so as ultimately to come against and bind upon the inserted object as shown by broken lines in Fig. 2. Thus the object will be tightly gripped and held properly centered. Whenever it is desired to use the article it is merely necessary to pull upwardly thereagainst. As soon as the weight is relieved from the conical unit 5, the spring 8 will urge it upwardly, thereby causing the wedges 10 to move upwardly and to spring radially so as to free the object located therebetween.

Any desired number of these units can be located in the rack, one being provided for each object to be supported and obviously objects of different thicknesses or diameters can be inserted into any one of the units provided the diameter is less than the normal distance between opposed arms 9 when in their normal or raised positions.

The pin 7 serves to limit the upward movement of the unit under the action of the tensioned spring 8.

45 What is claimed is:

1. A rack of the class described including a casing, a rigid member secured to the casing below the top thereof, there being coaxial openings in said member and top, a unit within the casing including a centering element, a stem thereon guided within the opening in the member, yielding means on the stem for supporting said element, resilient arms extending from said element and through the opening in the top, and outwardly extended wedges carried by the arms and

normally extended above the rack in position for downward wedging engagement with the walls of the opening in the top.

2. A rack for supporting long, slender articles, including a casing, a partition below and parallel with the top of the casing and secured to the casing, coaxial openings in the partition and the top of the casing, a conical unit interposed between said partition and the top of the casing, means depending therefrom for guiding the unit in the opening of the partition, a resilient support on the partition for the conical unit, resilient arms extended upwardly from said unit through the opening in the top of the casing, and means carried by the arms and cooperating with the wall of the top opening, for deflecting the arms inwardly toward each other when the unit is depressed under the weight of an article inserted between the arms and onto the unit.

3. The combination with a rack including a 20 casing having a top opening and an apertured portion beneath the top of the casing, of a funnel-shaped centering element within the apertured portion and coaxial with the top opening, yieldable supporting means mounted on the apertured 25

portion, relatively movable arms extending upwardly from said element and through the top opening, and means carried by the arms and cooperating with the wall of the opening for deflecting the arms inwardly toward each other when the unit is subjected to the weight of an article interposed between the arms, thereby to grip the object between said arms.

4. A rack for supporting long, slender articles 10 on end which includes a casing having a top opening, a funnel-like unit within the casing and coaxial with the opening, said unit having a depending stem, means for guiding the stem for up and down sliding movement, a yielding support for the unit mounted on the stem, arms extending upwardly from the unit and through the opening, wedges extending outwardly from the arms and positioned for deflection inwardly toward each other by the wall of the opening when the unit is depressed under the weight of an object inserted between the arms, said arms, when deflected, constituting means for gripping the inserted element.

WM. J. FISHEL.
